(57) CLAIM

The ornamental design for a clip-on golf ball holder, as shown and described.

DESCRIPTION

FIG. 1 is a front isometric view of the applicant's clip-on golf ball holder illustrating the new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a side elevational view thereof;

FIG. 7 is a rear isometric view thereof; and,

FIG. 8 is a front isometric view of a second embodiment of the design including a pair of golf tee holders and a ball marker holder.
